UNITED STATES PATENT OFFICE.

JAMES B. KIRBY, OF CLEVELAND, OHIO.

HANDLE-SWITCH FOR SUCTION-CLEANERS.

1,195,363.

Specification of Letters Patent. Patented Aug. 22, 1916.

Application filed November 27, 1914. Serial No. 874,318.

To all whom it may concern:

Be it known that I, JAMES B. KIRBY, a citizen of the United States, residing at Cleveland, in the county of Cuyahoga and 5 State of Ohio, have invented a certain new and useful Improvement in Handle-Switches for Suction-Cleaners, of which the following is a full, clear, and exact description, reference being had to the accompanying 10 drawings.

This invention relates to suction cleaners or other electrically operated devices of a nature to be pushed by hand along a level surface, the electrical mechanism being at 15 all times under the control of the operator.

The objects of this invention are the provision of a switch casing and switch operating mechanism which shall be more convenient, better fitted to the hand, more easily 20 manipulated, and less liable to be broken or injured by the incidents of use than other devices prior to my invention.

Other objects of the invention are the provision of a switch casing of great reliability, 25 simplicity, neatness, and ease of manufacture, and that can be easily applied to the handle and to which the flexible cord can be easily attached, and further objects and advantages will appear as the description proceeds.

In the drawings accompanying and forming a part of this application I have shown certain of the simplest and most preferable 35 embodiments with which I am familiar, though these are merely suggestive of many which may be employed.

In these drawings Figure 1 represents the complete cleaner in use, showing the mode of holding the same; Fig. 2 is a longitudinal sectional view through the end of the handle and switch casing; Fig. 3 is a transverse cross sectional view upon the line 3—3 of Fig. 2; and Fig. 4 is a longitudinal sectional view showing a modified form of cap.

45 Describing the parts by reference characters, 1 represents generally the casing of the cleaner, 2 the wheels that support the same, 3 the handle pivoted thereto by which the same is operated, 4 the dust bag, and 5 the 50 flexible cord by which the necessary energy is brought to the device. Cleaners of this nature are operated by being pushed and pulled over the floor somewhat after the manner of a common carpet-sweeper, the 55 length of the handle 3 being ordinarily about the same as that of a carpet-sweeper,

and in this mode of operation it is natural and customary for the user to keep the end of the handle at a point never above and generally a little below the waist line as 60 shown in Fig. 1. Also it is desirable to lead the cord 5 to the upper end of the handle rather than to the lower end since it is thus kept out of the way of the machine, and it is desirable to locate the electric switch for 65 starting and stopping the machine at the upper end of the handle since this avoids the necessity of stooping over and feeling about in some inaccessible part of the machine. Besides it is sometimes important to shut 70 off the power quickly. In order that the switch control may be immediately at the operator's hand, I form the switch casing itself as a handhold for this handle, employing, preferably, a standard switch of 75 the rotary pole type secured to a rotatable cap which terminates and forms a closure for the end of this casing. Also, in order to facilitate and expedite the turning of this cap I deflect the end of this casing downwardly so as to bring the same into a substantially horizontal position during its ordinary use as shown in Fig. 1, this being the position in which the turning of the cap can be most quickly performed. Preferably this 80 cap forms a continuation of the casing, and is preferably made with a roughened surface slightly larger in diameter than the casing so that the hand may obtain a firm grasp of the cap at all times that the cleaner 85 is in use. As here shown this casing consists of a hollow shell 6 having one end portion 7 of cylindrical shape adapted to receive the end of the handle 3 and having the other end portion 8 also of cylindrical 90 shape angularly related to the portion 7 and receiving the switch mechanism 9. My experience indicates that the angle between the portions 7 and 8 should be about 35° to 45°, though a small change in this regard 95 I consider immaterial to the invention. The portion 8 is generally of slightly larger diameter than the portion 7 in order to accommodate the switch mechanism, the latter being of any suitable kind though preferably 100 having an axial rotatable stud 10. Ordinarily I use a standard commercial switch whose body is of porcelain and whose stud is formed with a threaded portion 11 for the reception of the usual button.

110 In the simplest form of the invention the end of the shell is closed by means of a metal

cap as shown in Fig. 4, said cap in this instance consisting of a hemispherical portion 12 corresponding in diameter to the portion 8 of the casing and terminating in an abrupt shoulder 13, adapted to rest against the correspondingly abrupt end of the casing. Outside of the shoulder 13 the cap bears an integral cylindrical extension 14 closely embracing the portion 8 and knurled 10 or corrugated on its surface. Interiorly this cap is provided with an axial boss 15 having an internally threaded socket at its end adapted for the reception of the threaded portion 11 of the stud, which at the same 15 time secures the cap in place and provides the necessary driving engagement for operating the switch. This device provides all of the advantages necessary to the realization of the requirements heretofore expressed except that difficulty has sometimes been experienced with the breakage of the switches, since if the handle 3 be allowed to fall suddenly upon the floor, the bent shape of the switch casing causes this cap to strike first 20 and the blow is sometimes transmitted through the stud 15 with a sufficient force to shatter the porcelain 9. This difficulty is largely overcome by the square engagement of the shoulder 13, and is more liable to occur 25 in case the cap be not thoroughly screwed up against the end of the stud. In order to overcome this difficulty I have provided the arrangement shown in Fig. 2 wherein the cap is shown at 16 and similarly has a shoulder 30 17, though in this case I have illustrated it as provided with a cylindrical extension 18 adapted to fit inside of the casing 8 instead of outside as before. Immediately adjacent to the shoulder 17 is a slight enlargement 19 35 externally knurled or corrugated for a hand-hold as before. Interiorly this cap bears a fixed stud 20 to which is secured a hollow barrel 21 having at its outer end an internal flange 22 formed with a hexagonal or other 40 non-circular opening 23 as shown in Fig. 3. Projecting through this aperture is a similarly shaped connector 24 having at its inner end a head 25 slideable along the barrel. Between the head 25 and flange 22 is interposed 45 a coil spring 26, while the end of the connector is recessed and threaded as before for connection with the stud 10. When this cap is applied to the end of the casing the operation of the thread is to draw the connector 24 against the spring 26, thus pulling the shoulder 17 snugly against the end of the casing and also preventing the transfer of any damaging blows to the switch in case 50 the handle should fall on the floor.

60 The cap shown in Fig. 2 is formed of a composition of cementitious substance while that in Fig. 4 is formed of metal, the former being preferable since a non-conductor. The engagement of the shoulder 13 or 17 with the 65 end of the casing tends to shield the switch

mechanism in both cases while the enlargement of the portion 14 or 19 next to it causes the hand always to remain in contact with this cap whenever the cleaner is being employed, thereby bringing the control of the 70 motor continuously under the operator's hand.

The handle is preferably grooved for the reception of the wires 30 leading to the motor, the upper end of this groove being 75 preferably deepened for the reception of the cord 5. The end of this cord is preferably surrounded with a wire helix 31 to prevent kinking, and this is conveniently held in place by the switch casing itself. 80

While I have described the form shown in Fig. 2 as an improvement in certain respects over that shown in Fig. 4, I do not mean to indicate the latter as being part of the prior art since I claim both forms as my 85 invention as well as numberless other forms not specifically described but falling within the terms of the claims hereto annexed.

Having thus described my invention, what I claim is:

1. A switch casing for cleaner handles comprising a hollow shell having its end portions disposed at an angle to each other, one of said portions being adapted to receive the end of the handle and the other 95 having a rotatable cap fitted to the end thereof, and switch mechanism in said casing and operatively connected to said cap.

2. In a cleaner, a switch casing comprising a hollow shell having angularly related 100 portions one of which is adapted to receive the cleaner handle and the other the switch mechanism, the latter portion having a shouldered circular end, a cap fitted to said second portion and having a shouldered circular end facing the end of said casing, 105 said cap having an offset portion fitting against the wall of said casing and means for securing said cap operatively to the switch mechanism. 110

3. In a cleaner, a switch casing comprising a hollow shell having angularly related portions one of which is adapted to receive the cleaner handle and the other the switch mechanism, switch mechanism in said last 115 portion and having an axial threaded stud, a cap fitted to the end of said shell, a hollow barrel within said cap, a threaded connector non-rotatably mounted within said barrel but freely movable therewith, and a resilient member between said connector and the end of said barrel, said connector being screwed to the end of said stud. 120

4. In an electrically operated cleaner, a switch casing comprising a hollow shell having one end secured to the cleaner handle and the other end portion disposed at an angle thereto so as to be substantially horizontal during the normal use of the cleaner, switch mechanism in the last named portion 125 130

of the shell and having an axial threaded stud, and a rotatable cap fitted to the end of said shell and having a portion adjacent to said shell of larger diameter than said shell and exteriorly roughened.

5. In a device of the character described, the combination, with an operating handle, of a switch casing comprising a hollow shell and having one end secured to said handle, 10 switch mechanism in said shell and having a rotatable stud axial with the other end thereof, and a rotatable cap having a cylindrical portion overlapping the end of said

shell and having a convex terminal portion forming a rounded continuation of said shell, said cap being operatively connected to said stud and having its portion adjacent to said shell of greater diameter than said shell and exteriorly roughened. 15

In testimony whereof, I hereunto affix 20 my signature in the presence of two witnesses.

JAMES B. KIRBY.
